UNITED STATES PATENT OFFICE.

DAVID WILEY ANDERSON, OF SCOTTSVILLE, VIRGINIA, ASSIGNOR TO UNITED STATES FUEL SAVING EQUIPMENTS CORPORATION, OF CHARLOTTESVILLE, VIRGINIA.

AUTOMATIC HEAT-REGULATING AND FUEL-SAVING ATTACHMENT FOR HEATERS OF VARIOUS KINDS.

1,320,960.

Specification of Letters Patent.

Patented Nov. 4, 1919.

Application filed March 4, 1919. Serial No. 280,572.

To all whom it may concern:

Be it known that I, DAVID WILEY ANDERSON, a citizen of the United States, residing at Scottsville, in the county of Albemarle 5 and State of Virginia, have invented certain new and useful Improvements in Automatic Heat-Regulating and Fuel-Saving Attachments for Heaters of Various Kinds, of which the following is a specification.

10 This invention relates to a novel automatic heat regulating and fuel saving attachment for heaters of various constructions and types.

The main object of the invention is to provide an unusually simple, economical, novel and thoroughly efficient self-regulating attachment for heaters of various kinds which will readily demonstrate its automatic draft regulating and fuel saving qualities.

20 A further object of this invention is to so construct my improved attachment that it may be easily secured to or be formed integral with the outer casing of various types of stoves, furnaces and heaters, and will be automatically operated by the increased air 25 inlet current and gravitation, or by the increased or decreased atmospheric pressure which is occasioned by the increased or decreased intensity of the heat inside of the

30 stove or heater, together with gravity, thereby preventing the heater or stove from being overheated and also from getting too cold, thereby saving the time and trouble of having to frequently turn on and off the draft 35 dampers, as is now customary with the ordinary devices employed.

Another object of the invention is to provide a novel attachment which may be constructed of sheet or cast metal of any 40 suitable size, shape or thickness, that will be readily capable of meeting the required conditions of the stove, furnace or heater to which it may be attached.

Another object of this invention is to construct my novel attachment in the form of a hinged door provided with means for holding the loosely suspended dampers in a closed position, thus making said dampers partially or wholly inactive.

50 The foregoing and such other objects as may appear from the ensuing description are accomplished by the novel features of con-

struction, combination, location and arrangement of the parts hereinafter more fully described, illustrated in the accompanying drawings and particularly pointed out in the claims appended hereto, it being understood that slight changes in the form, proportions, and minor details of construction may be resorted to without departing from the spirit or sacrificing any of the advantages of the invention.

In the accompanying drawings, which form a part of the specification, it will be seen that:

Figure 1 is a sectional elevation, showing a portion of a stove or heater with the novel attachment embodying my invention secured thereto.

Fig. 2 is a perspective view, showing a portion of a heater with the attachment hinged thereto.

Fig. 3 is a sectional elevation of a portion of the heater casing with a slightly modified form of my novel attachment.

Fig. 4 is a similar view, showing a slight modification of the attachment, and

Fig. 5 is a sectional view similar to that shown in Fig. 1, showing another slight modification of the attachment.

Similar numerals of reference are employed to designate corresponding parts throughout the several figures of the drawings.

In carrying out this invention as illustrated, the numeral 1 designates the outer casing of any suitable or desirable type or construction of stove, furnace or heater, and attached to said casing, preferably at a point below the grate 2, by rivets, bolts or 90 suitable hinges 3, or formed integral therewith, is the attachment 4 provided with a flanged portion 5 by which the attachment is riveted, bolted, or it may be in the form of a door suitably hinged to the stove casing, as 95 shown in Figs. 1 and 2, and formed integral with the attachment 4, extending inwardly near its upper end, is a shouldered portion 6, terminating in a depending member 7, said portion 6 and member 7 extending entirely across the recessed portion 8 of the attachment, and secured to the lower end of the member 7 by a rule joint or suitably pivoted at 9 is an adjustable and detachable

wall or diaphragm 10, provided with openings 11 for the free passage of air therethrough, said wall 10 having an outwardly extending flange 12 formed integral with the bottom portion thereof, with a slotted opening 13 therethrough adapted to receive a threaded thumb screw 14 having a securing nut 15 fitted on its threaded end for firmly fastening the wall 10 in its suitably 10 adjusted position to the inwardly and upwardly inclined or curved lower wall 16, which terminates at its inner end with or without an upright air directing or conveying wall 17, said latter walls forming an integral part of the attachment. Loosely suspended from the lower face of the shoul- 15 dered portion 6 by S-shaped supports 18, or by any other suitable or desirable means, are a plurality of dampers 18' adapted to swing 20 perpendicularly with respect to the wall 10, to allow the free passage of air through the openings in the said adjustable wall, when not closed automatically by the atmospheric pressure, or by the closure fastening means 25 hereinafter described.

Pivots supported by the integral bearings or socket portions 19 formed on the outer face of the attachment is a swinging bail 19' having a weighted portion 20, adapt- 30 ed to counterbalance and cause the depend- 35 ing portion 21 of the bail to engage the outer face of the loosely suspended dampers and secure said dampers in their closed position when desired, thereby making said dampers partially or entirely inactive, and formed integral with the outer face of the attachment is a socket 22 or other suitable means 35 for holding the bail in its disengaged or released position, as clearly shown in Figs. 40 1 and 2.

In the slightly modified form of the attachment shown in Fig. 3 it will be seen that the attachment is secured to the heater by suitable means, and depending from the inner portion thereof and formed integral with its upper wall 23 is a depending mem- 45 ber 24, to which is secured the detachable and adjustable wall in the manner hereinbefore described, the bail 19' being suitably 50 supported by the depending bearings 25, formed at the outer end portion of the attachment, and the inner lower face of the attachment is formed on a curve 26 with a radius using the point 9 as a center, said 55 attachment being provided with a main air draft opening 27 having a suitable cover 28, and a downwardly and inwardly inclined member 29 serving to direct and guide the 60 passage of the air within the heater, the dampers being loosely suspended by suitable means depending from the lower surface of the top portion of the attachment.

By reference to the modified form shown in Fig. 4 it will be perceived that my attachment is provided with a downwardly and

inwardly sloping or inclined face portion 30 provided with an integral depending mem- 5 ber 31, to which is suitably secured an adjustable and removable wall or diaphragm 32, having an inwardly flanged portion 33 70 at its lower end, by which the said wall 32 may be suitably secured in its adjusted position to the inner curved face 34 of the attachment, the dampers being loosely sus- 75 pended from the top portion and adapted to swing perpendicularly with respect to the outer face of the attachment and the wall 32, the bail 19' being supported in any suit- 80 able or desirable manner for the purpose hereinbefore referred to, and the upper por- 85 tion of the attachment having an opening 35 therethrough for the direct draft, provided with a suitable cover 36.

The modification shown in Fig. 5 of the drawings shows a simple door 37 suitably hinged to the casing of a heater in a down- 85 wardly and inwardly inclined or sloping position, and to the upper portion of which is secured a plurality of loosely suspended dampers which are adapted to swing per- 90 pendicularly with respect to said door, so as to allow the free passage of air through the openings 38 formed therethrough when not closed by atmospheric pressure or held closed by the depending portion 21 of the 95 bail, which is carried by the door in any suitable or desirable manner.

It will be readily perceived that, although I have shown and described a plurality of dampers, a single damper loosely suspended 100 substantially in the manner described may be employed in connection with my novel attachment such as herein set forth.

Having thus described my invention, what I claim and desire to secure by Letters Patent is:

1. An automatic heat regulating attachment for heaters of various kinds, said attachment forming a portion of the outer wall or casing of the heater and provided with a plurality of openings therethrough, and a plurality of automatically operated dampers loosely suspended on the outer face of the attachment and adapted to open and close said openings, said dampers being ex- 110 posed to the outer air.

2. A device of the character described comprising an attachment secured to a heater, said attachment having a down- 120 wardly and inwardly inclined adjustable and detachable wall provided at its bottom with a slotted extension, means for securing said wall in its adjusted position, and a plu- 125 rality of loosely suspended dampers supported at the front of said wall adapted to swing with respect to said wall.

3. A device of the character described comprising an attachment secured to a heater, said attachment having a down- 130 wardly inclined adjustable and removable

wall provided at its bottom with a slotted extension, means for securing said wall in its adjusted position, a plurality of loosely suspended automatically operated dampers 5 supported at the front of said wall adapted to swing with respect to the wall, and means for securing said dampers in their closed position.

4. A device of the character described 10 comprising an attachment secured to a heater, said attachment having a downwardly and inwardly inclined adjustable and removable wall provided at its bottom with a slotted extension, an inward and upward curved portion near the bottom of the attachment, means carried by said curved portion for securing said wall in its adjusted position, a plurality of loosely suspended automatically operated dampers supported 15 at the front of the wall adapted to swing with respect to the wall, and means carried by the attachment for securing the dampers in their closed position and for releasing the said dampers.

20 5. A device of the character described comprising an attachment secured to a heater, said attachment having a downwardly and inwardly inclined adjustable and removable wall provided with a plurality 25 of openings therethrough, and a slotted extension at the bottom thereof, means for securing said wall in its adjusted position, means for securing the dampers in their closed position and for releasing them, and

means for securing the damper securing 35 means in its released position.

6. A device of the character described comprising an attachment secured to a heater, said attachment consisting of a downwardly and inwardly inclined wall 40 provided with a plurality of openings therethrough, and a slotted extension at the bottom thereof, means for securing said wall in its proper position, a plurality of loosely suspended automatically operated dampers 45 supported at the front of the wall, swinging means for holding the said dampers in their closed position, and means for securing said swinging means.

7. A device of the character described 50 comprising an attachment secured to a heater, said attachment consisting of a downwardly and inwardly inclined wall provided with a plurality of openings therethrough, and a slotted extension at its bottom, an inward and upward curved portion near the bottom thereof, means carried by the curved portion and fitted in the slotted extension for securing said wall in its proper position, a plurality of loosely suspended 60 automatically operated dampers supported at the front of the wall adapted to swing with respect to the wall, means for securing said dampers in their closed position, and means for securing said damper securing 65 means.

DAVID WILEY ANDERSON.
